UNITED STATES PATENT OFFICE.

WILLIAM E. LEMLEY, OF TAYLOR, WASHINGTON.

BUILDING BLOCK.

Application filed May 5, 1925. Serial No. 28,048.

This invention relates to masonry structures such as arches, sewers, water conduits, and the like.

The main object of the invention is the improvement in a water-tight wall structure of this character where permanency, and strength to withstand strains and stresses are of primary importance.

Another object is the provision of an improved form of building blocks which may be readily laid in interlocking relations in interlocking courses or tiers.

Another object is the provision of improved wall reinforcing means whereby the building blocks are coupled in a most rigid and efficient manner.

More specific objects and advantages of the invention will appear in the following description.

The invention is illustrated in the accompanying drawing, in which,—

Figure 1 is an end elevational view of a portion of a wall structure embodying my improvements; Fig. 2 is an underside plan view of parts shown in Fig. 1; Fig. 3 is a detail sectional view on line 3—3 of Fig. 2; and Fig. 4 is a perspective view of one of the wall blocks.

According to the present invention, a wall is composed of a plurality of blocks 5, preferably brick or tile; for a wall of an arcuate transverse shape, as illustrated in Fig. 1, the blocks 5 are correspondingly formed to provide inner and outer transversely curved surfaces.

Along one of its side edges a block is formed with a groove 6, shown herein as a reentrant angle, and along its other side edge with a correspondingly shaped ridge or projection 7 to provide interlocking joints between adjacent rows of blocks.

The ends of the blocks are also formed to provide interfitting connections, as shown a block at one end being provided at its outer side with a tongue 8 which protrudes beyond a shoulder 9 located at its inner side; the other end of the block being complementary thereto by the provision of a tongue 10 at its inner side which extends beyond a shoulder 11 located at the outer side of the block.

By such tongue-and-recess devices, the blocks are afforded overlapping end connections, one with another in each longitudinal row of blocks, as represented in Fig. 2.

To enable the blocks to be laid with their outer surfaces 12 and inner surfaces 13 flush

with the respective wall surfaces, and for the purpose of affording space for mortar or other cementatory material between the associated tongues, each of the latter is made of less thickness than the respective shoulders.

To reduce the weight of a block, the same is desirably molded or otherwise formed to provide therein longitudinally disposed air-spaces or channels 14 extending between the shoulder at one end of the block and the extremity of the tongue at its other end. The block is also advantageously provided with one or more air-spaces 15, and has apertures 16 extending longitudinally of the block between its shoulders 9 and 11 and preferably in proximity of the respective tongues.

In assembling, the blocks are arranged substantially as represented in Figs. 1 and 2 with plastic cement at the joints.

Reinforcement in the nature of tie-rods 17 are employed to extend through the aligned apertures 16 of two successive blocks, the projecting ends of the rods being bent to provide laterally directed hooks 18 to bear against the respective block-shoulders and with bill elements 19 extending, preferably, into the adjacent spaces 15.

The tie-rods thus arranged have their bent ends embedded in the mortar at the respective joints between associated tongues 8 and 10 to provide effective coupling means.

The tie-rods are furthermore disposed in a manner to couple each block with the block in front and to the rear thereof and thus cooperate to afford, in effect, a continuous reinforcement for the entire length of each longitudinal course of blocks.

What I claim, is,—

1. In a wall for a sewer or the like, the combination with a plurality of building blocks arranged in longitudinal rows and constructed with overlapped ends rabbeted to afford recesses between the overlapped ends of adjacent blocks in each row, of a plurality of independent tie-rods arranged in spaced apart relation both longitudinally and transversely of the wall in each row of blocks, each tie-rod extending through a pair of adjacent blocks of the same row and a filling material provided within said recesses for retaining the tie-rods, said tie-rods being arranged in staggered positions so that one tie-rod couples each block with the block in front and another tie-rod couples the same block to the block at the rear.

2. A wall for a sewer or the like comprising longitudinally disposed rows of spaced apart blocks, a filling material for the spaces intermediate the blocks, and independent tie-
5 rods extending through and formed of approximately the length of two blocks, the ends of said rods being bent and embedded in said filling for retaining the tie-rods, said tie-rods being arranged in staggered positions adjacent opposite sides of the blocks to cooperatively provide reinforcement the entire length of the wall.
- 10 3. In a wall section of the character de-

scribed, a plurality of blocks arranged in rows and having inter-engaging ends and 15 side edges, a tie-rod independently connecting each block with the next adjacent block at one end thereof, and a further tie-rod independently connecting the same block with the next adjacent block at the other end 20 thereof, each tie-rod being extended through and having its ends anchored at the outer ends of a pair of adjacent blocks.

Signed at Seattle, Washington, this 13th day of April, 1925.

WILLIAM E. LEMLEY.
